UNITED STATES PATENT OFFICE.

CHARLES H. TURNER, OF BELVIDERE, ILLINOIS.

COLLAR.

992,459.

Specification of Letters Patent. Patented May 16, 1911.

Application filed August 8, 1910. Serial No. 576,217.

To all whom it may concern:

Be it known that I, CHARLES H. TURNER, a citizen of the United States, residing at Belvidere, in the county of Boone and State 5 of Illinois, have invented certain new and useful Improvements in Collars, of which the following is a specification.

This invention relates to apparel collars, cuffs, and similar articles, and has for its 10 object to provide improved means for buttoning a collar or the like.

It is known that the edges of an ordinary buttonhole in collars become broken or torn after very little wear, caused by being 15 starched too stiffly, whereby the buttonholes break under the strain incident to buttoning the collar. My invention is designed to remedy this defect, by the provision of a pliable or flexible attachment located at the 20 button holes in the collar, which will enable the collar to be buttoned quickly and easily. The attachment has the further advantage that it will give more freedom to the collar, and ease to the wearer, as it will not bind 25 around the neck or under the chin, the connection to the shirt allowing a certain amount of movement so that the collar will accommodate itself to the wearer. By the means indicated the durability of the collar 30 is greatly increased, and the annoyance and difficulty incident to buttoning a stiff collar onto a shirt will be avoided.

The invention is illustrated in the accompanying drawings in which:

35 Figure 1 is a perspective view of the collar in open position; Fig. 2 is a section on the line 2—2 of Fig. 1; Fig. 3 is a perspective view of the collar in closed position.

Referring specifically to the drawings, 40 indicates a collar of ordinary or desired construction. The illustration shows a turn-down collar, but the invention may be used on other styles, as desired.

The buttonholes at the usual places in the 45 collar-band are indicated at 7, and they are modified, as compared to ordinary buttonholes, in the respect that they are made considerably larger, and preferably circular or with an enlarged eye at one end, the eye or 50 opening being larger than the head of an ordinary collar-button, so that the head is free to pass through said eye or opening

freely and without engagement with the edges thereof.

On the inner side of the collar-band, adjacent the said buttonholes, tabs or small flaps are placed. Those adjacent the front buttonholes are indicated at 8, and are attached at one end only. The attached end of the tab is preferably inserted in a slit at 55 9 in the inner ply of the collar-band, so that the end is located between the inner and outer plies, and is thus covered on both sides, and is fastened by stitches 10. The free end of the flap projects over the eye 7 and is 60 provided with a buttonhole 11, of ordinary type, which registers with said eye. The flap 12 at the back buttonhole is similarly attached at both ends, and is provided with a buttonhole 13 which registers with the eye 70 70 in the back of the collar-band. The flaps 8 and 12 are made of some pliable and flexible fabric which cannot be starched, such as silk, for example, and thus the flaps at all times remain pliable and limber, permitting 75 the collar to be buttoned without annoyance and increasing the durability thereof, by reason of the pliability of the tabs and also by reason of the fact that they may be made of superior material.

80 In applying the collar to a shirt, the buttons are first placed in the neck-band of the shirt, as usual, and the back button is then engaged in the buttonhole 13. The front ends are then drawn together and the front 85 button engaged in the buttonholes 11. The head of the buttonhole will pass freely through the eyes 7 in the neck-band, having only sufficient engagement therewith to prevent the ends of the band from slipping out 90 of proper position. The buttonholes in the tabs 8 serve to receive the strain on the collar, and also receive the wear incident to buttoning and unbuttoning the collar. The flexibility of the tabs permits a certain 95 amount of play to the collar, whereby it can adjust itself to the neck of the wearer or to the particular style of neckwear used. This avoids binding or chafing the neck, without in any manner impairing the appearance of 100 the collar. When the collar is buttoned the tabs are concealed, being located behind the ends of the collar-band, where they are crossed. Silk is the material preferably

used for the tabs or attachments, but rubber or any other material which will not become stiff when the collar is starched may be substituted.

5 I claim:

A collar or the like having enlarged button-receiving eyes, through which a button-head will pass freely, and also provided with buttoning tabs adjacent said eyes, said tabs

having buttonholes, and being made wholly of pliable material incapable of stiffening by starch.

In testimony whereof, I affix my signature in presence of two witnesses.

CHAS. H. TURNER.
